US0D1111188S

(12) **United States Design Patent** (10) **Patent No.:** **US D1,111,188 S**
(45) **Date of Patent:** **** Feb. 3, 2026**

(54) **NESTED PIPETTE TIP ARRAY ASSEMBLY**

(71) Applicant: **BIOTIX, INC.**, San Diego, CA (US)

(72) Inventors: **Juan Martin Mendez Padilla**, Tijuana (MX); **Arta Motadel**, San Diego, CA (US); **Peter Paul Blaszczak**, San Diego, CA (US)

(73) Assignee: **BIOTIX, INC.**, San Diego, CA (US)

(**) Term: **15 Years**

(21) Appl. No.: **29/825,099**

(22) Filed: **Jan. 28, 2022**

Related U.S. Application Data

(62) Division of application No. 29/759,427, filed on Nov. 23, 2020, now Pat. No. Des. 957,682, which is a division of application No. 29/692,493, filed on May 24, 2019, now Pat. No. Des. 906,538, which is a division of application No. 29/592,990, filed on Feb. 3, 2017, now Pat. No. Des. 854,185.

(57) **CLAIM**

The ornamental design for a nested pipette tip array assembly as shown and described.

DESCRIPTION

FIG. 1 is a top perspective view of a nested pipette tip array assembly showing our new design;

FIG. 2 is a bottom perspective view thereof;

FIG. 3 is a longer side view thereof;

FIG. 4 is a shorter side view thereof;

FIG. 5 is a top view thereof; and,

FIG. 6 is a bottom view thereof.

The broken lines depict portions of the nested pipette tip array assembly that form no part of the claimed design.

1 Claim, 6 Drawing Sheets
